DESIGN FOR A COMBINED BICYCLE GUARD AND LAMP

Tord Erik Daniel Bilde, Stockholm, Sweden

Application December 17, 1941, Serial No. 104,685

Term of patent 14 years

To all whom it may concern:

Be it known that I, Tord Erik Daniel Bilde, a subject of the King of Sweden and a resident of Stockholm, Sweden, have invented a new, original, and ornamental Design for a Combined Bicycle Guard and Lamp, of which the following is a specification, reference being had to the accompanying drawings, forming a part thereof, and of which:

Fig. 1 is a perspective side view of a combined bicycle guard and lamp showing my new design.

Fig. 2 is a side view of same on a larger scale,

Fig. 3 is a front view of the combined bicycle guard and lamp.

Fig. 4 a perspective view of the combined bicycle guard and lamp seen from the front and somewhat from above, and

Fig. 5 a perspective view of the combined bicycle guard and lamp seen from the front and from the left.

Portions of the guard in Figs. 2, 3, and 4 have been omitted or broken away for convenience of illustration.

I claim:

The ornamental design for a combined bicycle guard and lamp, as shown and described.

TORD ERIK DANIEL BILDE.
